UNITED STATES PATENT OFFICE.

WALTER J. DOAN AND HARRY C. DOAN, OF RICHMOND, INDIANA.

AUTOMATIC GRAVITY-VALVE.

1,156,837.

Specification of Letters Patent.

Patented Oct. 12, 1915.

Application filed January 2, 1914. Serial No. 809,967.

To all whom it may concern:

Be it known that we, WALTER J. DOAN and HARRY C. DOAN, both citizens of the United States, and residents of the city of Richmond, in the county of Wayne and State of Indiana, have invented a new and useful Construction in Automatic Gravity-Valves, of which the following is a full, clear, and comprehensive specification and 10 exposition, being such as will enable a mechanic to construct and install the same with exactitude.

Our invention relates to valves which are adapted to a great variety of uses, but it is intended more particularly to be attached 15 to radiators of steam-heating plants or the like.

The object of our invention, broadly speaking, is to provide an automatic gravity valve which will be entirely automatic in its operations after being installed, which will be neat and attractive in appearance, strong and durable in construction, reliable in its operations, not liable to become inoperative after long usage, and which can be manufactured, sold, and installed, at a comparatively low price.

A more specific object of the invention is to provide an automatic gravity valve for 30 steam-heating radiators so constructed that the pressure from inside the radiator may escape through the valve, but absolutely preventing the air outside the radiator from entering through the valve, thereby utilizing hitherto waste heat, dispensing with the necessity of opening and closing the valve manually and absolutely dispensing with the customary knocking incident to steam-heating plants.

As will be seen hereinafter our invention 40 will overcome all of the objections usually encountered in devices of this general character, as it will automatically open as the pressure increases in the plant, allowing the cooler air in the radiator to escape in advance of the warm air from the heater, thereby allowing the heated air to circulate freely and eventuating in the radiator being heated more quickly, and causing it to 50 maintain its maximum of efficiency. And when the heat supply is retarded or cut off, as during the night time when not attended to, and as soon as the pressure begins to decline, then our valve will automatically close 55 and will absolutely prevent outside air from being drawn into the radiator, on account

of the pressure of the outside air entering the dome and pressing into the cavity of the cup member 9 which has a large surface for the air to contact with, and thereby holding 60 the heat and causing the radiator to remain hot for a comparatively long period of time.

The principles of this invention involve the formation of a partial vacuum in the radiator as the steam pressure decreases and 65 recedes, for the reason that the valve will automatically close and prevent the entrance of outside air. Then when the pressure in the boiler again starts to increase it is apparent that the partial vacuum in the radiator will tend to pull the heat from the 70 boiler toward and into the radiator thereby accelerating the heating of the radiator and allowing it to attain its maximum efficiency 75 in a minimum of time.

One manner for the construction of our invention, that which seems to be the most practical, is shown in the accompanying drawings, in which—

Figure 1 is a side elevation of our invention complete and in operative position as attached to a radiator, the latter being indicated by dotted lines. Fig. 2 is a vertical central section taken through our invention. Fig. 3 is a plan view of the upper portion of 80 the device, the dome or top being removed. Fig. 4 is a perspective view of the cup-member alone. And Fig. 5 is a plan view of the upper portion of the device, the dome or top and also the cup-member being removed. 85

Similar indices denote like parts throughout the several views.

Referring now to the invention in detail: The body of our invention is indicated by the numeral 1, which we prefer to form 90 round in cross section, the same being provided with a bottom 2 which is preferably integral therewith, or securely connected thereto. Extending out from the body 1, and securely connected thereto, is the threaded nipple 3 which is adapted to be screwed in the radiator 4, the latter being indicated in dotted lines.

Extending inward horizontally from the upper end of the body 1 is the abutment 5. A central circular aperture is formed through the abutment 5, from the periphery of which is the downwardly tapering valve-seat 6 having a smaller opening in its lower end which forms the aperture 7, as indicated in Fig. 3, which leads into the chamber 8 of the body. By this arrangement it is 105 110

apparent that the body 1, the abutment 5, and the valve-seat 6 may be formed integral with each other, that is said parts may be formed from a single piece of sheet metal and pressed or stamped into the form shown.

Numeral 9 denotes the cup-member of the valve, the same being formed tapering, and it is adapted to fit in the valve-seat 6. The diameter of the upper end of said cup-member 9 is the same as the upper diameter of the valve-seat 6, while the diameter of the lower end is the same as that of the lower end of the valve-seat 6. Said cup-member 15 9 is provided with a bottom, which is integral with the tapering wall thereof, as is indicated in Fig. 2. The upper edge of the cup-member 9 is notched or corrugated, as indicated at α in the drawings, in which 20 notches or corrugations the baffle 12 is adapted to engage when the cup-member is forced upward in contact therewith, in order to prevent the cup-member from spinning around. Also, if the baffle 12 be dispensed with, the notches or corrugations α 25 will prevent the aperture 11 from being shut off should the cup-member 9 engage the top of the dome 10, as the air will be permitted to escape through said notches or corrugations.

Numeral 10 denotes the dome or cap, whose diameter is slightly greater than is the diameter of the body 1, the upper end of which it is adapted to close, the dome 35 being threaded or otherwise detachably connected to the upper end of the body, substantially as shown. Formed through the dome 10 is a comparatively small aperture or vent 11, as is indicated in Fig. 2.

Numeral 12 denotes a spring baffle which 40 extends horizontally across above the cup-member 9, and which is located at such distance therefrom as to allow the cup-member to rise from its seat, but preventing it 45 from becoming deflected and displaced, and also preventing it from contacting with the dome and closing the vent 11. One end of the said baffle may be secured to the inside 50 of the dome 10, but its other end should be free in order to act as a spring against which the upper end of the cup-member may resiliently impinge should it be carried upward with considerable force.

In practice the device is connected to a 55 radiator in such manner that the interior of the radiator will be in connection with the interior of the chamber 8. Therefore as the pressure increases in the radiator it is evident that the cool air therein will be 60 free to pass through the stem 3 into the chamber 8, then lifting the cup-member 9 it will pass into the dome 10 and from the latter it will escape through the vent 11, thereby allowing the radiator to clear itself 65 and therefore providing a circulation from

the steam generator outward through our valve, and thereby allowing the hot steam to quickly fill the radiator, and as a small amount of pressure will continue to escape through the vent 11 it is evident that the 70 radiator will continually receive the maximum of heat, which manifestly could not be the case if no escape were provided from the interior of the radiator. Now as soon as the pressure in the radiator commences 75 to decrease, then the cup-member will automatically seat itself in the valve seat, and the outside air will be prevented from entering the radiator and driving back the hot air, which manifestly would accelerate the 80 cooling of the radiator with consequent loss of heat incident thereto.

It should be observed that by reason of the shape of the cup-member 9 the outside air will have a maximum pressure thereon 85 from above to hold it seated against the inlet of outside air, and also gravity will assure the cup-member righting itself, and will also contribute to holding the cup-member in its seat.

We would have it understood that various minor changes may be made from that herein in set forth without departing from the spirit of our invention and without sacrificing any of the advantages thereof.

95

Having now fully shown and described our invention, what we claim and desire to secure by Letters Patent of the United States, is—

1. An automatic gravity valve for steam radiators, comprising a main body having a chamber therein, a bottom closing the lower end of said body, an abutment extending inwardly from the upper end of the body and having a central aperture therethrough, a valve-seat tapering downwardly from said abutment, a cup-member corresponding with said valve seat and adapted to contact therewith and to close both the aperture in the abutment and the aperture in the valve seat, the interior of the cup-member opening upward, a dome detachably secured on the upper end of the body and having a vent formed through its upper end, and resilient means for preventing the cup-member from contact with the dome, all substantially as shown and described.

2. An automatic gravity valve, comprising a body having a chamber therein, a stem extending out from the body and adapted to be connected to a radiator, an abutment formed integral with the upper end of the body, a downwardly tapering seat formed integral with the center of the abutment and extending down therefrom, a cup-shaped valve member adapted to rest in said seat and opening upward and having notches formed in its upper edge, a dome detachably secured on the upper end of the body and having a vent aperture formed 125 130 135 140 145 150 155 160 165 170 175 180

therethrough, all substantially as shown and described and for the purposes set forth.

3. An automatic gravity air valve comprising in combination a main body, a downwardly convergently formed valve-seat located in and concentric with said body with a central aperture therethrough at its lowest point, a stem extending out from the body and located below the valve seat, there being inlet means through the stem to said aperture, a downwardly tapering valve member adapted to contact with all of the valve seat and close said aperture, the same being entirely free to be raised by pressure which may enter through said stem

and adapted to automatically close by gravity when said pressure is removed, a cap removably connected around the upper end of the body and extending thereabove, there being a small aperture formed through the top of said cap to allow egress of air when the said valve member is lifted.

In testimony whereof we have hereunto subscribed our names to this specification in the presence of two subscribing witnesses. 25
